WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

MECHANICAL WARP STOP MOTION

Application filed November 2, 1928. Serial No. 316,835.

This invention relates to improvements in mechanical warp stop motions and it is the general object of the invention to provide a motion wherein the knocking-off of a shipper handle and the operation of a detecting part of the mechanism may be actuated by a single lever acting in conjunction with a yieldable element supported by the lever and tending to give the detecting elements their regular movements.

The invention relates more particularly to the type of motion shown in Reissue Patent No. 14,829 to Regan and Patent No. 1,360,638 to Holmes. Mechanisms of this type have ordinarily been provided with a knock-off mechanism of the type shown in the Regan patent, but in that motion there is a pivoted dog which is mounted on a movable member, the dog being held in inoperative position through the action of a light spring. It is an important object of my present invention to simplify the type of motion shown in the Holmes patent and eliminate the spring.

It is a further object of my present invention to provide a cam lever which shall have pivotally mounted on one end thereof a weighted element and a regularly moving actuator member which is given a rising and falling motion preferably on every alternate beat of the loom, the mechanism being so organized that the weighted element is effective to move the actuator member to inoperative position when there is no fault in the warp.

It is a further object of my present invention to provide a knock-off mechanism wherein there is employed a knock-off lever symmetrical about a plane perpendicular to its axis so that the same may be used either to create tension in a pull rod to effect knock-off or to push the rod forwardly to stop the loom, depending upon which position the knock-off lever occupies.

With these and other objects in view which will appear as the description proceeds, my invention resides in the combination and arrangement of parts hereinafter described and set forth in the claims.

In the accompanying drawings, wherein

a convenient embodiment of my invention is set forth,

Fig. 1 is a vertical transverse section taken through a loom having my improved warp stop motion applied thereto, the parts being shown in running and non-detecting position in full lines and in knocking-off position in dotted lines, 55

Fig. 2 is a side elevation of the warp stop motion on an enlarged scale showing the parts in non-detecting position in full lines, 60

Fig. 3 is a side elevation taken in the direction of arrow 3, Fig. 2, and

Fig. 4 is a top plan view of the actuator lever taken in the direction of arrow 4, 65 Fig. 1.

Referring particularly to Fig. 1, I have shown a loom frame 10 as being provided with the usual bottom shaft 11 which is given a complete revolution every second 70 pick of the loom by mechanism not shown. The shipper handle 12 is mounted on the shipper shaft 13 and operates through mechanism not shown to keep the loom in operation when in the forward full line position, but acts to stop the loom when in the rear dotted line position shown in Fig. 1.

A suitably supported rod 14 has secured thereto the depending hub 15 of a head frame 16 through which extends a plurality of horizontally aligned bushings 17. Each bushing is free to rotate in the head 16 and has secured thereto a link 18 which prevents movement of the bushings through the plate 16 to the right as viewed in Fig. 3. Each bushing is fitted to a non-circular detector rod 19 which extends through slots in the drop wires D and is operatively related to its bushing to be oscillated about its axis during the normal running of the loom. The lower ends of the links are pivoted to a connector 20, the effect of the connector 20 being to cause all of the rods 19 to oscillate in unison. The matter thus far described may be substantially the same as that shown in the aforesaid patents and forms no part of my present invention. 85

In carrying my improvements into effect I provide the head 16 with an upwardly projecting horn 30 from which projects laterally 90

a stud 31 on which is pivotally mounted a knock-off lever 32. The latter has a vertically extending arm 33 to the extremity of which is pivoted a rod 34. The latter by means of a coupling 35 is connected to a second rod 36 which extends loosely through a portion 37 of the shipper handle 12. A collar 38 is secured in adjusted longitudinal position along the rod 36 and is positioned for engagement 10 with the portion 37.

The horizontally extending arm 39 of the lever 32 is so placed as to be directly over a vertically reciprocating actuating member 40 and when engaged by the latter will cause 15 rocking of lever 32 in a right hand direction as viewed in Fig. 1 to move the shipper handle from the full to the dotted line position. Said actuator rod or member 40 is adjustably secured at its lower end to a weighted element 20 41 movable freely about a stud 42 mounted on a cam lever 43. The latter is supported by a stud 44 held in fixed position by a bracket 45 mounted on the loom frame 10. A second bracket 46 has adjustably secured 25 therein a stop screw 47 located under a weighted projection 48 of the weighted member 41 extending to the left of stud 42.

The right hand end of the cam lever 43 is provided with a roll 49 which cooperates with 30 a cam 50 having a roll depressing face 51. The cam is secured to the bottom shaft 11 and as set forth herein will cause an oscillation of the cam lever 43 every other pick of the loom.

35 The upper end of the actuator member 40 extends through a horizontal projection 52 which is formed as a part of the left hand link 18 as viewed in Fig. 2. This extension is integral with the lower part of the corresponding link and when moved angularly will cause rocking movement of the detector rods 19. The upper end of the actuator is free to move through a perforation 53 formed in the projection 52 as shown in Fig. 3.

45 In operation, the bottom shaft 11 will rotate constantly to cause a periodic elevation every other pick of the loom of the stud 42 on the cam lever. Prior to the beginning of the raising of stud 42 the weighted end 48 50 will rest on the screw 47, but as the stud 42 rises there will be a tendency on the part of the weighted member 41 to move in a counter-clockwise direction around stud 42 with the weighted end 48 supported by the screw 47. Such an action will tend to move the upper end of the actuator rod 40 to the left as viewed in Fig. 1 and as said member 40 passes through the projection 52 the latter will tend to impart angular movement as 55 previously described to the detector rods 19. If all the drop wires D are raised the tendency of rods 19 and 40 to move will not be resisted, the upper end of the actuator rod 40 being movable to the left to assume the dotted line position shown in Fig. 2 when there is no

fault in the warp so that a continued upward movement of said member 40 will carry the latter to one side of the horizontal lever 39 of the knock-off lever. Under these conditions, therefore, the knock-off rod 34 will remain at rest and the shipper handle will therefore remain in running position.

When a fault occurs in the warp, however, a drop wire D will fall to arrest angular movement of its detector rod 19. The upper 75 narrow end 70 of slot 71 in the drop wires D, one of which is shown in Fig. 2, acts to prevent oscillation of the rods 19 when the drop wires are down, as set forth in the aforesaid patents.

80 As the cam 50 continues to rotate the stud 42 will be moved to its lowest position due to the weight of the member 40 which serves to hold the roll 49 against the cam and under these conditions the actuator member 40 will be moved to the right or restored to the full line position shown in Figs. 1 and 2. This position as shown clearly in Fig. 2 corresponds to the vertical position of the detector rods 19 so that the latter can be engaged by 90 the restricted slot 70 in the drop wire should any one of the latter be in lower position.

When there is warp fault one of the drop wires will be down and the corresponding rod 19 will be held against oscillation so that 95 as stud 42 rises the member 40 will not be permitted to move to the left. The weight 48 will move upwardly away from the supporting screw 47 and the member 40 will move longitudinally with no appreciable angular motion and as the cam 50 continues to rotate the upper end of the member 40 will engage the horizontal arm 39 of the knock-off lever and rock the latter to the dotted line position shown in Fig. 2. This action on the part of the knock-off lever will stop the loom by throwing the shipper handle 12 from the full to the dotted line position shown in Fig. 1 as previously described.

100 By referring to Fig. 3 it will be seen that the knock-off lever 32 is symmetrical about a plane passing through the arms 33 and 39 perpendicular to the stud 31 and lying intermediate the forks 60 of said arm 33. A stop pin 61 may project from the horn 30 to engage the arm 39 and limit angular movement to the left of the knock-off rod 34, movement of said rod 34 to the right being limited by collar 38 and extending portion 37 of the shipper handle, as shown in Fig. 1.

105 It will also be seen that the stud 31 is located high enough above the links 18 to permit inversion of the lever 33 if desired so that the arm 33 will tend to occupy the dot and dash position shown in Fig. 2. When in this position the rods 34 and 36 will be placed under tension so as to create a pull where the shipping mechanism is such as to require this type of motion. It is to be understood of course that my invention is not limited to the 110 115 120 125 130

particular form of shipper handle set forth herein and that the motion on the part of the arm 33 either to the right or to the left may be employed to effect stopping of the loom.

5 From the foregoing it will be seen that I have provided a warp stop motion wherein a single cam and lever act to permit a weighted member to cause rocking of the detector rods and also stopping of the loom at the time of warp fault. It will further be seen that the adjusting screw 47 may be varied to change the location of the upper end of the member 10 40. It will also be seen that the knock-off 15 lever is so designed that the same may be reversed on its stud so as to transmit either a compressing or a tensioning force to the knock-off rods.

Having thus described my invention it 20 will be seen that changes and modifications may be made therein by those skilled in the art without departing from the spirit and scope of the invention and I do not wish to be limited to the details herein disclosed, but 25 what I claim is:

1. In a warp stop motion, a detector rod to be oscillated about the axis thereof, a loom 30 stopping mechanism, a regularly moving driving means having a periodic movement, a weighted actuator pivotally mounted on the means and having operative connection with the detector rod, said actuator member moving toward the stopping device when the means has a periodic movement and tending 35 by its weight to move to one side of the stopping device and to oscillate the detector rod, the detector rod when held against movement causing engagement of the stopping device by the actuator member.

40 2. In a warp stop motion, a detector rod to be oscillated about the axis thereof, a loom stopping mechanism, a regularly moving driving means having a periodic movement, a weighted actuator member pivotally mounted 45 on the means and movable with the latter, a support for the weighted member to hold the latter in alignment with the stopping device when the means is in one position, mechanism establishing an operative connection 50 between the actuator member and the detector rod, said weighted member when the means moves to the other position tending through said mechanism to oscillate the detecting rod and remain in contact with the 55 support to move the member out of alignment with the stopping device, and said member moving away from the support when the means moves to the said one position and the detector rod is held against movement to 60 cause engagement of the stopping device by the actuator member.

65 3. In a warp stop motion, a detector rod non-circular in cross section to be oscillated about its axis, a stopping device to be moved at the time of warp fault to stop the loom,

a regularly moving lever having regular working and non-working strokes during the operation of the loom, a weighted actuator member pivoted to the lever, a support for the actuator member to hold the same in 70 normal position in alignment with the stopping device when the lever is beginning its working stroke, and means establishing a connection between the detector rod and the actuator member, the actuator lever on its working stroke tending to lift the weighted actuator member and the latter remaining on the support therefor when the member turns angularly with respect to the lever to communicate motion through the connection to the detector rod and move said member out of alignment with the stopping device, and said actuator member moving with and being lifted from the support therefor into engagement with the stopping device when the detector 80 85 rod is held against oscillation.

4. In a warp stop motion, a detector rod non-circular in cross section to be oscillated about its axis, a stopping device to be moved at the time of warp fault to stop the loom, a 90 lever having regular working and non-working strokes during the operation of the loom, a weighted element pivotally mounted on the lever and extending substantially horizontally, a support for said element, an actuator rod 95 extending upwardly from the element and normally in alignment with the stopping device when the lever is beginning its working stroke, means establishing an operative connection between a rod secured to the weighted element and the detector rod whereby movement of the actuator rod out of alignment with the stopping device will cause oscillation of the detector rod, said weighted element acting when the lever moves on its working stroke to move the actuator rod out of alignment with the stopping device when the detector rod is free to rotate, and said means between the rods causing the weighted element to be moved away from the support as 100 the lever moves on its working stroke and effect engagement between the actuator rod and the stopping device when the detector rod is held against rotary movement.

105 5. In a warp stop motion, a detector rod 110 non-circular in cross section to be oscillated about its axis, a stopping device to be moved at the time of warp fault to stop the loom, a regularly moving lever having regular working and non-working strokes during the operation of the loom, a link moving with the detector rod and having a guide opening therein, a weighted element pivotally mounted on the lever and having a portion to extend through the guide opening, a support for the weighted element independent of the lever, said support holding the weighted actuator element in such a position when the lever is beginning its working stroke as to be in alignment with the stopping device and to move 115 120 125 130

the detecting rod to a detecting position, and said weighted actuator member when the lever moves on its working stroke tending to remain in contact with the independent support therefor to cause movement of the link and oscillation of the detector rod and also to move the actuator member out of alignment with the stopping device, said detector rod when held against oscillation acting through the link to hold the actuator member in alignment with the stopping device and move the weighted element away from the independent support therefor when the lever moves on its working stroke.

15 In testimony whereof I have hereunto affixed my signature.
